UNITED STATES PATENT OFFICE

JAMES R. BYRNE AND DANIEL J. MACINTOSH, OF LIVERPOOL, NOVA SCOTIA, CANADA

AUTOMATIC CROSSING GATE

Application filed March 19, 1931. Serial No. 523,863.

This invention relates to railroad crossing gates and more particularly to an automatically operated crossing gate structure.

An object of this invention is to provide an automatically operated crossing gate which is actuated upon movement of the train within a block or section adjacent the crossing so as to lower the gate prior to the arrival of the train at the crossing.

Another object of this invention is to provide in a gate structure of this kind means whereby the gate will be raised by movement of the train through the block.

A still further object of this invention is to provide hydraulic means actuated by engagement with the train structure whereby the gate is lowered and raised by contact of the train structure with the gate operating structure.

The above and various other objects and advantages of this invention will in part be described in and in part be understood from the following detailed description of the present preferred embodiment, the same being illustrated in the accompanying drawings, wherein:

Figure 1 is a detail side elevation of the device constructed according to the preferred embodiment of this invention;

Figure 2 is an enlarged sectional view taken on the line 2-2 of Figure 1;

Figure 3 is an enlarged sectional view taken on the line 3-3 of Figure 1;

Figure 4 is a detail side elevation of the pressure releasing member;

Figure 5 is a fragmentary sectional view of the pressure releasing valve operated by the pressure releasing member;

Figure 6 is a fragmentary side elevation partly in detail of the swivel mounting for the gate structure, and

Figure 7 is a detail end elevation partly in section of a gate operating structure of this kind connected to two gates.

Referring to the drawings wherein like numerals of reference designate corresponding parts throughout the several views, the numeral 10 designates generally a pair of railroad rails of conventional construction, and

the numeral 11 designates generally a cross-

ing gate structure which is rockably mounted on a supporting post 12, the free end of the gate structure 11 traversing the road and engaging a post 13 which is disposed on the roadway oppositely from the support 12.

The gate structure 11 comprises an elongated gate or bar member 14 which is pivotally mounted on the support 12 by means of a pivot 15 and the inner end of the gate structure 11 is provided with a weighted member 15' for normally swinging the bar 14 in open or upright position.

In order to automatically lower the gate structure 11, I have provided a pressure member generally designated as 16, which comprises a cylinder 17 within which a piston 18 is slidably mounted. A shaft or bar 19 is connected to the piston 18 by means of a ball joint 20 which is held within a socket 21 of the piston head 18 by means of a plate 22 and the piston rod 19 extends outwardly through the top of the cylinder 17 and is provided at the upper end thereof with a bore 23 for receiving a shaft or bar 24 which extends upwardly therefrom.

A spring 25 is disposed about the shaft 24 and at the lower end thereof engages against a plate or ring 26, and the upper end of the spring 25 engages against an outstanding lug 27 which is mounted on a swivel member generally designated as 28. A washer or plate 29 is interposed between the upper end of the spring 25 and the swivel head 27 and the shaft 24 is adapted to have sliding movement within the swivel head 27. The swivel member 28 is pivoted to the gate structure 11 by means of a pivotal member 30, which pivot 30 is mounted in the gate structure 11 rearwardly of the pivot 15 so that upon upward movement of the swivel member 28, the opposite or outer end of the gate structure will be lowered.

A gasket 31 is secured to the piston head 18 and slidably engages the inner surface of the cylinder 17. The cylinder 17 is provided with an inlet port 32 adjacent the bottom thereof and an outlet port 33, which inlet and outlet ports are disposed adjacent the bottom of the cylinder, and a normally closed overflow port 34 which is disposed interme-

diate the upper and lower ends of the cylinder 17 and is preferably disposed at a point adjacent the end of the upward travel or movement of the piston 18 and is opened 5 when the piston 18 rises thereabove. The inlet port 32 of the pressure member 16 is connected to a pump 35 or the like by means of a connecting pipe 36. This pump 35 is adapted to force a liquid into the gate operating member 16, and comprises a cylinder 37 which at one end thereof has an outlet port 38 which is in communication with the gate operating member 16 by means of the connecting pipe 36.

15 A piston generally designated as 39 is slidably mounted in the cylinder 37, and a connecting rod 40 is carried by the piston 39 and extends outwardly through the head 41 of the cylinder 37. The cylinder 37 is provided with an intake chamber 42 which communicates with the interior of the cylinder 37 by means of an intake port 43 or the like. The piston 39 is provided at the lower end thereof with a gasket 44 which at the periphery thereof engages the inner surface of the cylinder 37. The central portion of the piston 39 is preferably reduced, as at 45, so as to provide an intake chamber 46 about the piston 39, which chamber communicates 20 with the intake chamber 42 by means of a port 46', and a second gasket 47 is mounted on the piston 39 adjacent the upper end thereof and cooperates with the lower gasket 44 for sealing the piston within the interior of 25 the cylinder 37. A partition or inner wall 48 is mounted within the cylinder 37 at a point spaced upwardly from the lower end thereof, and is provided with a port 49 which is in communication with the cylinder 37 and 30 40 an outlet chamber 50 which is disposed between the lower face of the partition 48 and the lower end of the cylinder 37.

An annular plate 51 is mounted in the cylinder 37 and is provided with an opening 52 therethrough which aligns with the opening 49, and a gasket or resilient washer 53 is interposed between the plate 51 and the partition 48, this gasket 53 having an opening therethrough aligning with the openings 49 and 52, so that liquid within the cylinder 37 can pass through the partition and the outlet chamber 50 into the connecting pipe 36. A check valve 54 is mounted within the cylinder 37 engaging against the gasket 53, and 55 a spring 55 engages the stem 56 of the check valve so as to constantly urge the check valve 54 into closed position.

This check valve 54 is provided so as to permit the movement in one direction only 60 of liquid through the cylinder 37. A plate 57 is carried by the valve stem 56 and engages the upper end of the spring 55. The lower end of the spring 55 is disposed in a recess or groove 58 in the plate 51. The 65 plate 51 is also provided with an annular

groove 59 within which one end of the expanding spring 60 is seated, the opposite end of the expanding spring 60 engaging against the lower gasket 44 which is secured to the piston 39 so as to constantly urge the piston 70 upwardly within the cylinder 37. The connecting rod 40 is loosely mounted at the lower end thereof in the piston 39 and the extended portion of this piston rod is provided with a laterally extending arm 61 75 which is interposed in the path of the flange of the wheel rotating on the rail 10.

An upstanding post 62 is mounted on the head 41 of the cylinder 37 and is provided at the upper end thereof with an inwardly 80 extending arm 63 which extends inwardly toward the piston rod 40. The piston rod 40 is also provided with a suitable member 64 which engages against the stud 62 so as to limit the rotary movement of the piston 85 rod 40. A spring 65 is disposed about the piston rod 40 and one end of the spring 65 engages the stop pin 64 carried by the piston rod, and the other end of the spring 65 is anchored to the head 41 of the cylinder so that 90 the piston rod will be rotated or swung by the spring 65 so as to constantly maintain the pin 64 in engagement with the stud 62 and coercively keep the arm 61 within the 95 path of the flange 66 of the car wheel.

Through the use of the rotatable piston rod 40 and the stop members 62 and 64, the piston rod 40 will be forced inwardly of the cylinder 37 upon engagement with the flange 66 of a wheel moving in one direction 100 over the rail 10 but a wheel moving in the opposite direction over the rail 10 will swing the arm 61 outwardly of the rail 10 and also swing the stop pin 64 away from the stud 62 under the tension of the spring 65. The intake chamber 42 is connected to a liquid supply tank 67 by means of a connecting pipe 68, and the supply tank or reservoir 67 has a filling pipe 69 whereby the tank may 110 be maintained in filled condition at all times. The pipe 68 is connected preferably to the tank 67 adjacent the bottom thereof so that the liquid will gravitatingly flow toward the pump or pressure member 35.

A releasing member generally designated as 70 is mounted between the rails 10 and at a point remote from the pump or pressure member 35, this releasing member 70 comprising a supporting structure 71 within which a vertically movable member 72 is 115 slidably mounted, this member 72 having a head 73 which is projected into the path of the flange 66 of the car wheel. The head 73 at each end thereof is preferably tapered so that the impact of the rotating wheel will 120 not injure the head. An expanding spring 74 is mounted within the base 71 and constantly urges the slidable piston 72 upwardly. A stem 75 is secured to the piston 72 and extends downwardly through the base 71. A 125

releasing valve structure generally designated as 76 is mounted on a support 77 and one end of the valve structure 76 is connected to the tank or cylinder 16 by means of a connecting pipe 78 which at the opposite end is connected to the outlet port 33 of the cylinder 17.

The opposite end of the valve structure 76 is connected by means of a pipe line 79 to the tank or reservoir 67 closely adjacent the top thereof. A rock arm 80 is connected to the valve structure 76 and rockably engages the stem 75 so that upon vertical movement of the stem 75, the rock arm 80 is rocked so as to open or close the valve 76. The overflow port 34 of the cylinder 17 is connected to the tank 67 by means of a connecting pipe 81, which pipe is connected to the tank 67 above the normal level of the liquid disposed therein. The spring 74 of the releasing member 70 is adapted to rock the valve 76 into a normally closed position and upon downward movement of the stem 75, the valve 76 is rocked into open position so as to permit the liquid within the cylinder 17 to pass through the valve structure and the pipe line 79 back to the tank 67.

In the operation of this device, the pump or pressure member 35 is preferably mounted on an angle so that the impact of the flange 66 will be substantially at right angles to the movement of the piston rod 40. As each wheel flange 66 strikes the operating arm 61 of the piston 40, the piston is moved downwardly in the cylinder 37 and the spring 60 will bring the piston 39 back into operative position. This reciprocation of the piston 39 will force the liquid through the check valve 54 and the connecting pipe 36 into the gate operating member 16. The filling of the cylinder 17 will force the plunger or piston 18 upwardly within the cylinder 17, which movement will lower the gate structure 11. The gate 11 will be held in lowered position during the entire movement of the train within the block defined by the pump 35 and the releasing member 70. As each wheel flange 66 strikes the operating lever or arm 61, the pressure within the cylinder 17 will be increased and when the piston 18 is moved upwardly to a point where the overflow port 34 is exposed, the liquid will flow through this overflow port and back through the pipe line 81 into the reservoir 67. This overflow port 54 is of sufficient size so that the piston 18 will be maintained in upraised position by the pressure within the cylinder 17. The outlet port 33 is normally open and as the cylinder 17 is being filled with liquid, the liquid may also pass through the pipe 78 to the valve 76 which is normally closed. However, as soon as the wheel flanges 66 strike the head 73 of the releasing member 70, the valve 76 will be rocked into open position so as to cooperate with the overflow port 34 in releasing

the pressure of the liquid within the cylinder 17. It will, of course, be understood that the pump or pressure member 35 is disposed at a point remote from the gate structure 11 on one side of the crossing, this point being any desired distance away from the crossing so that the gate will be lowered by the pressure of the liquid within the cylinder 17 before the engine or the front end of the train reached the crossing. The releasing structure 70 is disposed on the opposite side of the crossing from the pump 35 and after the forward end of the train passes the crossing and the wheel flanges 66 strike the releasing head 73, the pressure in the cylinder 17 will be released and the liquid permitted to gradually flow back through the return pipe 78. The weighted end 15 of the gate structure 11 will also operate to apply pressure to the liquid within the cylinder 17 so as to force this liquid outwardly of the cylinder 17 and permit the lowering of the piston 18 therein for raising of the outer end of the gate bar 14.

While we have shown a guard structure mounted on only one side of a crossing, we do not wish to be limited to this construction as, if desired, a pair of gate members may be operated by means of connecting shafts and gears, so that each side of the tracks will be closed to vehicular traffic when the train enters the gate operating block.

It is, of course, understood that various changes and modifications may be made in the details of construction and design of the above specifically described embodiment of this invention without departing from the spirit thereof, such changes and modifications being restricted only by the scope of the following claims.

As shown in Figure 7, a vertically disposed shaft 82 is rotatably mounted on the support 12 and operatively connected to the pivot 15 by means of gears or the like, and a horizontally disposed shaft 83 is operatively engaged with the shaft 82 by means of gears or the like, this horizontal shaft 83 being extended beneath the rails and connected at the opposite end to a second vertically disposed shaft 84 which is mounted on an upright 12'. A second gate 11' is rockably mounted on the support 12 and the pivot 15' of this gate is operatively connected with the vertical shaft 84 by means of gears or the like so that when the operating member 16 rocks the gate 11, the gate 11' will be rocked simultaneously therewith so that both sides of the rails will be guarded by gate structures.

We claim:

1. A crossing gate and operating means therefor, comprising a pivoted gate, means for constantly urging said gate into open position, a cylinder having an intake port near the bottom and a normally open outlet port intermediate the ends of the cylinder, a piston slidably mounted in said cylinder and con-

nected to said gate whereby to swing said gate into closed position upon movement of the piston in one direction, said piston closing the outlet port when the gate is open and opening the outlet port when the gate is closed, a pressure member interposed in the path of a car wheel for operation thereby, means connecting the pressure member to the cylinder whereby upon operation of said pressure member to move said piston beyond the outlet port and coercively swing said gate into closed position, and a releasing member connected to said cylinder and interposed in the path of the car wheel whereby to release the pressure in the cylinder, said gate upon release of the pressure in said cylinder being adapted to automatically swing into open position.

2. A crossing gate and operating means therefor, comprising a gate, supporting means for pivotally mounting said gate, a weight carried by the gate whereby to normally swing said gate into open position, a cylinder disposed adjacent said gate and having a normally open outlet port intermediate the ends thereof, a piston slidably mounted in said cylinder and controlling the opening and closing of the outlet port, means connecting said piston to said gate whereby to swing said gate downwardly into closed position upon outward movement of said piston in said cylinder, a pressure pump remotely positioned from said gate, means connecting said pressure pump to said cylinder, means carried by said pump and interposed in the path of a car wheel whereby to operate said pump through contact with the car wheel, a pressure releasing member remotely disposed from said pump and said gate, and means connecting said cylinder with said releasing member whereby to release the pressure in said cylinder upon contact of said pressure releasing means with the car wheel.

3. In a crossing gate and operating means therefor, a pressure member connected to said operating means, said pressure member including a cylindrical member having a normally open outlet port intermediate the ends thereof, a piston slidably mounted in said member and closing the port in one cycle thereof and opening the port in another cycle, a liquid reservoir, connecting means connecting said reservoir with said pressure member, a check valve carried by said pressure member whereby upon movement of said piston to permit the passage of a liquid through said cylinder in one direction, and means carried by the piston and interposed in the path of a car wheel whereby to move said piston longitudinally in said cylinder upon contact of the car wheel with said latter named means.

In testimony whereof we hereunto affix our signatures.

JAMES R. BYRNE.
DANIEL J. MACINTOSH.
